F. R. OLIVER.
COOLING APPARATUS,
APPLICATION FILED AUG. 21, 1916.

1,233,393.

Patented July 17, 1917.

Inventor

F. R. OLIVER

By *Watson E. Coleman*

Attorney

UNITED STATES PATENT OFFICE.

FREDERICK R. OLIVER, OF SAN FRANCISCO, CALIFORNIA.

COOLING APPARATUS.

1,233,393.

Specification of Letters Patent. Patented July 17, 1917.

Application filed August 21, 1916. Serial No. 116,128.

To all whom it may concern:

Be it known that I, FREDERICK R. OLIVER, a citizen of the United States, residing at San Francisco, in the county of San Francisco and State of California, have invented certain new and useful Improvements in Cooling Apparatus, of which the following is a specification, reference being had to the accompanying drawings.

10 This invention relates to an improved cooling apparatus for root beer and similar beverages and has for its primary object to provide simple and efficient means for cooling the beverage as it is dispensed from 15 the container or receptacle.

It is a more particular object of the invention to provide an apparatus for the above purpose embodying an outer barrel or container having double walls, a receptacle 20 supported within said container, said receptacle being of such form and dimensions as to provide an ice compartment within the container, a dispensing valve mounted upon the container wall, a pipe coil within the 25 ice compartment connected to the container and to the valve, and a second pipe coil in said compartment connected to the valve at one of its ends and adapted to be connected at its other end to a pressure tank containing 30 carbonated water or other liquid.

It is a further general object of the invention to improve and simplify the construction of apparatus of the above character and render the same highly serviceable 35 and convenient in practical use and capable of manufacture at relatively small cost.

With the above and other objects in view, my invention consists in the novel features 40 of construction, combination and arrangement of parts to be hereinafter more fully described, claimed and illustrated in the accompanying drawing, in which,

Figure 1 is a vertical sectional view of a liquid cooling apparatus constructed in accordance with the preferred embodiment of 45 my invention;

Fig. 2 is a horizontal section taken on the line 2—2 of Fig. 1;

Fig. 3 is a top plan view, the cover being 50 partly broken away; and

Fig. 4 is an enlarged detail vertical section showing the means for mounting the receptacle within the barrel or container.

Referring in detail to the drawing, 55 designates generally the container which is preferably of barrel-shape form as shown,

and has a head 6 permanently fixed in one end thereof. Within this container 5, a cylindrical shell 7 is arranged, said shell being preferably constructed of sheet metal 60 and open at its upper end. Suitable supporting feet 8 are provided upon the bottom of the shell 7 to space the same from the bottom 6 of the container. A spacing ring 9 is arranged between the upper open end 65 of the shell 7 and the wall of the container 5, said ring fitting into a V-shaped groove or chime in the container wall, and said spacing ring and the shell 7 being fixed to said wall by means of screws, bolts, or other 70 suitable fastening elements. The shell 7 is provided adjacent to its lower end with a laterally projecting outlet neck 10 extending through an opening in the wall of the barrel or container 5. Upon the outer end 75 of this neck 10, a dispensing valve 11 is suitably mounted or connected.

Within the shell 7, the receptacle 12 for the root beer or other liquid is arranged. This receptacle, as shown in Fig. 2, is of 80 substantially semi-circular form in plan and is spaced from the side and bottom walls of the shell. A plurality of screws 13 extend through the side walls of the receptacle adjacent to its upper end and through openings in the shell 7, the outer ends of said screws being threaded in the wall of the barrel or container 5. The pipes 14 are also connected to the receptacle adjacent its upper and lower ends and extend outwardly 85 through the shell 7 and the container wall, and to the outer ends of said tubes the upper and lower ends of the gage glass 15 is suitably coupled, whereby the quantity of liquid in the receptacle 12 may be readily 90 ascertained. The space within the shell 7 not occupied by the receptacle 12, constitutes an ice compartment, and broken ice is adapted to be packed therein beneath said receptacle and around the same. To the 100 inner side of said receptacle, at its lower end, one end of a pipe coil 16 is connected, and the other end of said coil extends outwardly through the neck 10 and is connected to the bore or passage of the valve 11. This 105 coil is disposed entirely at one side of the receptacle 12 and does not extend beneath the same. A second circular pipe coil 17 is disposed below the plane of the coil 16 and also has one of its ends leading to the 110 bore or passage of the valve 11. The other end of this latter pipe coil 17 extends down-

wardly through a tube or nipple 18 centrally mounted in the bottom 6 of the container 5 and in the bottom wall of the shell 7. A hose or tube extending from a pressure tank is connected to this latter end of the pipe coil and supplies carbonated water or other liquid to the pipe coil. A drain or waste pipe 19 extends some distance above the bottom wall of the shell 7 and downwardly through the bottom 6 of the container, so as to permit a sufficient amount of ice water to remain in the bottom of the shell 7 and partially cover the pipe coils.

Asbestos or other suitable packing material is tightly packed into the lower end of the container 5 around the shell 7 to conserve the ice and prevent the too rapid melting thereof. The root beer or other syrup is pumped through a pipe, indicated at 20, which extends up through the bottom of the container 5 and through the shell 7 into the receptacle 12 to a point adjacent the upper end of the latter. This pipe, at its lower end projecting through the bottom of the container 5, is equipped with a suitable threaded coupling for connecting the hose or other conduit thereto extending from the source of supply.

The top or cover for the container 5 consists of two similar semi-circular wood sections 21 which are hingedly connected along their straight edges, as at 22. A metal plate 23 is secured upon the top surface of each of these sections 21 and projects beyond the outer edge thereof to provide a marginal flange adapted to seat upon the upper edge of the container wall. It will be understood that the receptacle 12 which is preferably constructed of porcelain, may also be provided with a removable cover or closure.

Within the barrel or container 5, between the wall thereof and the shell 7, a casing 24 is suitably secured to the container wall, and a glass plate 25 containing suitable advertising matter is arranged in the wall of the container opposite this casing. Artificial illuminating means, indicated at 26, is provided within the chamber back of this plate. A pipe 27 leads from the top of the casing 26 upwardly through an opening in one of the top or cover sections 22 to exhaust the heated air from said casing. As this advertising device constitutes the subject-matter of a separate application for patent filed August 2, 1916, Serial No. 112,883, the same will not be further referred to.

From the foregoing description, taken in connection with the accompanying drawing, it is believed that the construction, manner of operation and several advantages of my improved cooling apparatus will be clearly and fully understood. By means of the same, ice-cold mixed drinks may be quickly served while the expense incident to the

refrigeration or the cooling of the liquid is relatively small. It is apparent, of course, that the apparatus may be manufactured in various sizes and also of other shapes than that shown in the accompanying drawing. The invention is also susceptible of many modifications in the form, proportion and arrangement of the several detail parts and I, therefore, reserve the privilege of adopting all such legitimate changes as may be fairly embodied within the spirit and scope of the invention as claimed.

Having thus fully described my invention, what I desire to claim and secure by Letters Patent is:—

1. A cooling apparatus including a container having inner and outer spaced walls, a liquid receptacle arranged within the container, means for sustaining said receptacle with its side and bottom walls spaced from the corresponding walls of the container to afford an ice compartment between said walls, the inner wall of the container having a laterally projecting outlet neck extending through an opening in the outer container wall, a valve operatively connected to said outlet neck, a pipe coil arranged in the bottom of the ice compartment and connected at one of its ends to the liquid receptacle and at its other end to said valve, and a drain pipe extending through the bottom walls of the container and above the plane of the pipe coil therein.

2. A cooling apparatus including a container, a shell arranged within the container having its side and bottom walls spaced from the corresponding walls of the container, a liquid receptacle arranged within said shell at one side thereof, means to sustain said receptacle in spaced relation to the side and bottom walls of the shell to afford an ice compartment, said shell having a laterally projecting outlet extending through the container wall, a valve operatively connected thereto, a pipe coil arranged in the bottom of the shell at one side of the receptacle connected at one end to the receptacle and at its other end to said valve, a second pipe coil arranged in said shell having one end connected to the valve and its other end extending centrally downwardly through the bottom of the shell and the container and adapted to be coupled to a source of liquid supply, and a waste pipe extending through the bottom of the container and the shell and above the plane of the pipe coils therein.

3. A cooling apparatus including a container, a shell arranged within the container having its side and bottom walls spaced from the corresponding walls of the container, a liquid receptacle arranged within said shell at one side thereof, pipes connected to the upper and lower ends of the receptacle and extending outwardly through the

wall of the shell and the container and serving as additional supports for the receptacle, a glass gage tube operatively connected to the outer ends of said pipes, means 5 to sustain said receptacle in spaced relation to the side and bottom walls of the shell to afford an ice compartment, said shell having a laterally projecting neck extending through the container wall, a valve operatively connected thereto, a pipe coil arranged in the bottom of the shell at one side of the receptacle connected at one end to the receptacle and at its other end to said valve, a second pipe coil arranged in said shell hav-

ing one end connected to the valve and its 15 other end extending centrally downwardly through the bottom of the shell and the container and adapted to be coupled to a source of liquid supply, and a waste pipe extending through the bottom of the container and 20 the shell and above the plane of the pipe coils therein.

In testimony whereof I hereunto affix my signature in the presence of two witnesses.

FREDERICK R. OLIVER.
